FREDRIK GRAF, OF KROKSLÄTT, SWEDEN.

DOFFING APPARATUS FOR SPINNING AND TWISTING MACHINES.

1,384,449.

Specification of Letters Patent. Patented July 12, 1921.

Application filed December 22, 1919. Serial No. 346,618.

To all whom it may concern:

Be it known that I, FREDRIK GRAF, engineer, a citizen of the Canton of Thurgau, of The Confederated Swiss Republic, and residing at Krokslätt, Sweden, have invented certain new and useful Improvements in Doffing Apparatus for Spinning and Twisting Machines, of which the following is a specification.

10 The present invention relates to a device in spinning or twisting machines adapted for the simultaneous removal of all the full bobbins or cops on the row of spindles on a spindle rail in the machine, and afterward simultaneously mounting empty tubes or pins in place of the full bobbins. The essential characteristic of the invention is that in front of the row of spindles on either side of the machine is arranged a shifting 15 apparatus consisting of a rod which can be moved up and down, rotated, and moved to and from the spindles, and which in front of each spindle carries two holders, of which the one in one position of the rod is intended for a full bobbin and the other for an empty tube, with the object that when the empty tubes mounted on the spindles have been filled with yarn they may be removed from the spindles by the holders on the 20 lifting of the rod, whereupon the rod is moved away from the spindles and turned a half revolution, and is again approached to the spindles, and then lowered, when the empty tubes in the other holders are passed 25 upon the spindles in order in their turn to be filled with yarn.

30 A form of construction of the said automatic doffing apparatus arranged on a spinning machine, is illustrated in the accompanying drawings. Figure 1 is a cross sectional view of the spinning machine, while Fig. 2 is a partial front elevation of the machine at one end of the same. Figs. 3 to 14 show details.

45 With reference to Fig. 1, 1 is one of the two end frame pieces of the machine to which the spindle rails 2 are fixed, one on either side of the machine. As the arrangements on both sides of the machine 50 are exactly alike, only those on one side of it will be described below. At each end of the spindle rail there is hinged to it a rod 3, which is so arranged that the upper end of the rod can be moved outward and 55 again be carried back into its original upright position, as is indicated by Figs. 1,

11 and 14. On the rod 3 there is fitted a sleeve 4 which is threaded on the outside, and so arranged that it can be rotated but not longitudinally displaced upon the rod. 60 The said sleeve 4 is provided with a nut 5, and on its upper end is mounted a bevel gear wheel 6 which meshes with a bevel gear wheel 7 on a shaft 8, which latter extends from one end frame of the machine 65 to the other, and which at each end carries, in addition to the wheel 7, also a hand wheel 9. In the upper part of the machine there is arranged a rotatable shaft 10, Fig. 1, which extends between the two end frame 70 pieces of the machine and is fitted in bearings carried by said pieces. On each end of the shaft 10 there is mounted a ratchet wheel 11, a hand wheel 12, and also a rope pulley 13, or the like, from which extends, 75 as indicated in Fig. 1, to each side of the machine, a wire rope, link chain, or the like, 14, the other end of which is attached to the frame work which carries the bevel gearing 6, 7, and the shaft 8 and which has 80 a projection 15, the end of which rests against a spring 16 on the end frame piece of the machine, when the said frame-work and parts appertaining thereto assume the position shown to the left in Fig. 1. The 85 ropes 14 which run over the guide rollers 17 are so connected to the rope pulley 13 that on the rotation of the shaft 10 they are simultaneously wound on, or off, the rope pulley and the rods 3 are thus simultaneously either moved into an upright position (as shown at the left in Fig. 1) or are lowered outwardly from that position (as shown at the right in Fig. 1). This outward movement is started by the springs 16, 90 which press the projections 15 outward the lowering movement being continued in virtue of the weight of the parts. The two rods 3, one on each side of the machine, thus in reality always have the same inclination, though in Fig. 1 they are shown at different inclinations, in order to illustrate their movements more clearly. With the aid of the ratchet wheel 11, the rods 3 can 100 be retained at any desired inclination.

105 When the shaft 8 is rotated, which can be done by means of one of the hand wheels 9 at either end of the machine, the bevel gearing 7, 6 at each end of the shaft, causes a rotation of the two threaded sleeves 4, 110 whereby the nuts 5 upon the same, which serve as the terminals of a rod or shaft 18

- connecting them, are simultaneously raised or lowered. The two gearings and the two sleeves are exactly similar to one another, and moreover the gearings are so arranged that when one of the sleeves is rotated in one direction, the other is simultaneously rotated in the same direction, in consequence whereof the rod 18, whether it is raised or lowered, always performs parallel motion.
- 10 This rod 18, which extends along the entire length of the spindle rail, and is situated at a suitable distance from the row of spindles, carries opposite each spindle two holders 19 of some suitable construction, into which tubes easily can be inserted and from which the tubes easily can be removed. The two holders 19 in front of each spindle are placed diametrically opposite each other, and all the holders along the entire rod are so mounted in relation to one another that at the same time one holder is facing each spindle. In order to render such an adjustment of the holders possible, each end of the rod 18 is rotatably connected with its nut 5, and is moreover provided with a hand-wheel 20 and a double ratchet wheel 21, 22 with teeth in opposite directions, for which there are pawls 23, 24, carried by arms 25 projecting from the nut.
- 30 When the bobbins 26 in the machine have been filled, with yarn, the shifters, with the aid of a hand-wheel 12, are moved into the positions shown at the left in Fig. 1 and Fig. 9, whereupon the shifters at either side of the machine may be operated independently of each other. In moving the shifters into the position shown in Fig. 9, the rod 18 is brought down into its lower position, and the head 27 on each tube 28 is clasped in this position by a holder 19. All the bobbins on the spindle rail can now be removed from their spindles by setting the shafts 8 in rotation with the aid of the hand-wheel 9 and thereby rotating the threaded sleeves 4, so that the rod 18 is raised into its top position as shown in Fig. 10, when the under sides of the tube heads 27 are above the upper ends of the spindles 29. When the bobbins have been removed from their spindles, the two shifters of the machine are brought into the position shown in Fig. 11 by rotating the hand-wheel 12, whereby the ropes 14 are unwound from their pulleys, the shifters being first moved outwardly by the springs 16 and afterward lowered by their own weight, and stopped after having moved so far outward that the rod 18 with the full bobbins 26 now carried by the same, as well as the empty tubes 28 which have been inserted in the other holders 19, can be turned half a revolution without being hindered by the spindles 29 (see Fig. 11). After this revolution of the rod 18, the shifters are again approached to the spindles, Fig. 12, by rotating the hand-
- 5 10 15 20 25 30 35 40 45 50 55 60 65 70 75 80 85 90 95 100 105 110 115 120 125 130
- wheel 12, whereby the ropes 14 are again wound up on their pulleys. The empty tubes 28 are now above the spindles 29, so that when the rod 18 is again lowered by rotating the threaded sleeves 4, the tubes are placed on their spindles, as shown in Fig. 13. As soon as the tubes have been placed on their spindles, the shifters are first lowered into an intermediate position, for instance into the position shown in Fig. 14 in dotted lines, in which position the rods 18 are moved to the other or outer ends of the threaded sleeves 4, whereupon the shifters are brought down into the position shown in Fig. 14 in full lines, in order to allow the bobbins 26 to approach the spindle rail. While the shifters assume this position, the tubes last mounted on the spindles are filled with yarn, and at the same time the full bobbins 26 in the shifter are removed by hand, and into the same holders from which they are removed, are inserted empty tubes, so that when the bobbins, which are being filled with yarn, are ready and the shifters are restored to the upright position, the empty tubes which are to be mounted on the spindles in place of the full bobbins are in place in the shifters. When the shifters are carried from their lowered position to the upright position, they are stopped, as in the case of the lowering, in an intermediate position, for instance the position shown in Fig. 14 in dotted lines, the rods 18 being then moved down into their lower position close up to the spindle rail, in order that the holders 19, when the shifters are brought into the upright position, may approach and clasp the heads of the tubes on the spindles, as shown in Fig. 9. The shifters provided with empty tubes now again assume the positions which are required in order to remove the full bobbins from the spindles and in their place to mount empty tubes, which operation is carried out in the manner above described.
- When the empty tubes are to be mounted on their spindles by the lowering of the rod 18, it is obviously of the greatest importance that they be in line above the spindles. In order to effect the exact adjustment required, special devices are provided. On the one hand the holders, which embrace the heads of the tubes and by which the bobbins are carried, are so arranged on the rod 18 that the distance between adjacent holders is precisely equal to the distance between the spindles, whereby an exact lateral adjustment of the tubes is effected. In order that an exact adjustment may also be had in the transverse direction an arrangement is provided with the object that, when the rod 18 is turned from the position shown in Fig. 10 into that shown in Fig. 12, this turn may be precisely 180°.
- To the ends just mentioned the rod 18 is

constructed in a special manner, as illustrated in the drawing, where in Figs. 3 and 4 a form of construction thereof is shown. Fig. 3 shows part of the rod, viewed from the side, and Fig. 4 the same part, seen in plan partly in section. This composite rod, which in the above description has been designated generally as 18, which designation, however, is not used in these figures, consists of an inner rod 30, on which are mounted alternately plates 31 and tube pieces 32 and 33 serving as distance pieces for the said plates. The plates 31 are arranged in pairs, and each pair forms such a holder as has been designated above as 19. The plates in each pair are held spaced apart by a tube piece 32 of such length that the head 27 of a tube can enter between the plates and the tube be retained in the required position by the same, whereas the length of the tube pieces 33 is such that the tubes 27 carried by the plates are spaced apart a distance equal to the distance between the spindles. In order that the plates may assume a definite position on the rod 30 without being able to turn on the latter, the rod is flattened along its entire length and the aperture 34 in the plates, Fig. 5, is shaped in conformity with the cross section of the rod 30. In each holder the plates 31 on the sides facing each other are provided with grooves or recesses 35 into which enter the rings on the heads of the tubes, so that the latter can be securely held in the desired position by the plates, which are somewhat yielding. The recesses 35 are shown in Fig. 6, which is a section along the line 6—6 in Fig. 5.

For the purpose of limiting the rotation of the rod 18, as mentioned above, to 180° there is provided in one or more places along the length of the rod a special guide, which consists of a rod 36 hinged to the spindle rail and a corresponding slide piece 37, (Figs. 3, 4, 7 and 8) fitted into the rod 18. This slide piece, the length of which is equal to the length of a tube piece 33, is provided with threaded side pins 38, which are of the same diameter as the rod 30, which, where a slide piece 37 is arranged, is split transversely. At the dividing points the ends of the rod 30 are threaded, and each of these ends together with the corresponding pin 38 is screwed into an internally threaded tube piece 32. In the slide piece 37 is arranged a diametrical perforation 39, which is of the same diameter as the rod 36 and into which the latter enters in order to serve as a guide. The slide piece is surrounded by a sleeve 40 provided with an aperture for the rod 36 and a projection 41, in which the end of the rod 36 is intended to stop, whereby the sleeve will be rendered stationary when the rod 18 composed of the rods 30, the tube pieces 32, 33, the holders, and the slide pieces 37, is rotated. It will be readily understood that by this arrangement the required turning of the rod 18 180° is easily attained. When the shifter has been raised to the position shown in Fig. 10, the end of the rod 36 has passed entirely out of the slide piece 37, but is still in the projection 41, in consequence of which the sleeve will be stationary, while the rod 18 as well as the bobbins and tubes carried by the same are rotated from the position shown in Fig. 10 to that shown in Fig. 12. Only when the rod has turned 180° is it possible to move down the rod 18 and the empty tubes carried by the same from the position shown in Fig. 12 to that shown in Fig. 13. In this movement the projection 41, in which the upper end of the rod 36 is situated before the movement commences serves as a guide for the rod, so that it can easily enter the aperture which has been brought opposite to it in the slide piece 37. The rod 36 also serves as a guide for the empty tubes, when these are mounted on the spindles, as well as for the full bobbins when they are removed from the spindles, whereby these will obtain rectilinear movement and the rod 18 will be prevented from turning during the downward as well as the upward movement.

Having now described my invention, what I claim as new and desire to secure by Letters Patent is:

1. In a doffing apparatus for spinning and twisting machines, oppositely disposed threaded supports movable toward and away from the machine adjacent the spindle rail thereof, a holder rod extending between said supports and having its ends engaging and movable lengthwise on said supports from end to end of the latter, holders on said rod, movable with the latter from end to end of said supports and means for rotating the holders.
2. In a doffing apparatus for spinning and twisting machines, the combination with oppositely disposed threaded supports pivotally mounted adjacent the ends of the spindle rail of the machine, of nuts adapted to travel lengthwise of said supports, a holder-supporting member attached to said nuts, holders on said member, and means for rotating said holders.
3. In a doffing apparatus for spinning and twisting machines, the combination with oppositely disposed threaded supports pivotally mounted adjacent the ends of the spindle rail of the machine, of nuts adapted to travel along said supports, a holder rod having its opposite ends journaled in said nuts, holders carried by said rod, and means for rotating said rod to present the holders successively in proximity to the spindle rail.
4. In a doffing apparatus for spinning and twisting machines, the combination with pivotally supported holder rods at opposite sides of the machine, of a pulley located centrally of the machine, cables extending

- 4
- from the pulley to the holder rods, and means for rotating said pulley to move the holder rods toward and away from the spindle rails of the machine.
5. In a doffing apparatus for spinning and twisting machines, a cop-holder-support comprising a rod, a sectional sleeve thereon, and spacer members interposed between the ends of the sleeve sections and projecting beyond the same.
6. In a doffing apparatus for spinning and twisting machines, a cop-holder-support comprising a rod, a sleeve thereon consisting of sections varying in length, and spacer plates interposed between the ends of the sleeve sections and projecting beyond the same.
7. In a doffing apparatus for spinning and twisting machines, the combination with a cop-holder-support comprising a rod having a transverse opening therethrough, of a guide rod pivoted to the machine and slidably extending through the opening in said first mentioned rod.
8. In a doffing apparatus for spinning and twisting machines, the combination with a cop-holder-support comprising a rod having a transverse opening therethrough and a sleeve surrounding the rod and having an opening therein registering with the opening in the rod, of a guide rod pivoted to the machine and slidably extending through the openings in the sleeve and said first mentioned rod.
9. In a doffing apparatus for spinning and twisting machines, the combination with a cop-holder-rod, of a perforated guide member having threaded ends engaging said rod, a perforated sleeve surrounding said member and having a projection extending therefrom, and a guide rod pivoted to the machine and adapted to reciprocate through said perforations, and to be retained in said projection.
10. In a doffing apparatus for spinning and twisting machines, the combination with a cop-holder rod, of cop-holders projecting therefrom and each comprising a pair of parallel projecting plates having grooves therein.
11. In a doffing apparatus for spinning and twisting machines, the combination with a pair of threaded sleeves pivotally mounted at each side of the machine, of means for moving said sleeves toward and away from the machine, a rod rotatably supported by the nuts at each side of the machine, pairs of oppositely projecting cop-holders projecting from each rod at intervals, each of said cop-holders comprising a pair of recessed plates, and means for rotating said rods.

In witness whereof I have hereunto set my hand in presence of two witnesses.

FREDRIK GRAF.
